CEMENT BASKET

Reuben C. Baker, Coalinga, Calif., assignor to
 Baker Oil Tools, Inc., Huntington Park, Calif.,
 a corporation of California

Application July 19, 1937, Serial No. 154,455

1 Claim. (Cl. 166—10)

This invention relates to appliances used during the operations of sinking an oil well bore and particularly pertains to devices of the character disclosed in my prior United States Letters Patent No. 1,561,768.

In this prior patent I have shown a collapsible basket structure circumscribing a well casing at a point along its length below cementing points in the casing so as to create a barrier between the casing and the wall of the well bore to enable trapping of cavings and prevent downward movement of cement discharged from the cementing ports. In this manner the blank casing of a combination string may be cemented in without the cement reaching the perforated pipe or the producing zone. It has various other uses, such as enabling cementing off of intermediate water sands.

In this prior patent the basket was constructed of an inverted frusto-conical canvas bag secured to a plurality of longitudinally extending flexible arms secured at their lower ends to the casing and flaring outwardly so as to engage the wall of the hole and hold the upper end of the bag in contact therewith.

It is the principal object of my present invention to provide a generally improved collapsible basket structure of the character above discussed which is entirely metallic in construction and which will properly conform to the contour of the bore without chance of by-pass openings due to folding or wrinkling.

One form which the invention may assume is exemplified in the following description and illustrated by way of example in the accompanying drawing, in which:

Fig. 1 is a view partly in side elevation and partly in vertical section disclosing the preferred form of my invention.

Fig. 2 is a plan view thereof partly in transverse section.

Fig. 3 is a transverse sectional view taken on line III—III of Fig. 1.

Fig. 4 is a view in elevation of one of the "petals" forming the basket.

Fig. 5 is a view in side elevation showing the cement basket connected in a cementing string.

Referring more particularly to the accompanying drawing, 10 indicates what is commonly known as a cement basket for use in forming a barrier between a well casing or tubing and the wall of the bore.

This device consists of a nipple 11 or a section of well casing or tubing or other cylindrical member which may be incorporated in a string of casing or tubing.

Arranged about the exterior of this member 11 at equally spaced distances apart are ribs 12 formed of flat flexible spring steel or other suitable material. The lower ends of these ribs 12 are secured by welding or otherwise to the member 11. From their lower ends the ribs extend upwardly of the member at an angle thereto so as to form an inverted frusto-conical framework about the member 11.

The upper extremities of the ribs 12 are curved inwardly and then upwardly to slidably engage the periphery of the member 11 as illustrated.

Secured to the inner face of each rib 12 is a "petal" 14 formed preferably of flexible sheet brass or other similar and suitable material. Each petal is narrower at its lower end than its upper end so when assembled the "petals" will form an imperforate inverted frusto-conical basket surrounding the member 11. The "petals" overlap as illustrated so that the basket may be collapsed about the member 11 but the inherent spring qualities of the ribs 12 will tend to maintain it fully expanded.

From the foregoing and from the drawing it is obvious that the present cement basket is made up of a number of circumferentially overlapping individual metal "petals" held in place with reinforcing spring steel ribs. The normal condition of the upper end of the basket is expanded so that it will conform to the diameter of the hole into which the member 11 is run on the well casing or tubing. When running in the hole, the upward force of the mud fluid tends to close in the "petals" to more or less conform to the outside diameter of the member 11 so that any distortion of the basket while it is being lowered into the hole is thus avoided. Immediately upon the member 11, or the casing or tubing upon which the basket is mounted, coming to rest in the bore, the mud pressure on the basket assembly is relieved, permitting the "petals" to expand to their normal position with the upper portion of the basket forming a seal against the wall of the hole.

It is thus obvious that thereafter cement or other material may be ejected from the casing or tubing, or member 11, above the basket, and that the latter will prevent its passing downwardly into the space around the tubing or casing below the basket.

The present device has a varied number of uses, but its principal use is on a combination string, that is, a single string of well casing composed of an upper section of blank casing and a lower section of perforated casing, which is to be run into the producing zone. The basket is posi-

tioned between these two sections so that the section of blank casing may be cemented off without the cement reaching the producing zone.

While I have shown the preferred form of my invention, it is to be understood that various changes may be made in its construction by those skilled in the art without departing from the spirit of the invention as defined in the appended claim.

Having thus described my invention, what I claim and desire to secure by Letters Patent is:-

In combination with a well tubing, a frustoconical basket therefor arranged about the exterior thereof with its smaller end tightly embracing said tubing and with its upper and larger end of a diameter normally considerably larger than the exterior diameter of the tubing and

concentric with respect thereto, said basket comprising a plurality of flexible metallic ribs spaced equal distances about said tubing and secured at their lower ends thereto and extending longitudinally thereof with their upper ends spaced radially outward from the tubing, and a "petal" like segment of relatively thin flexible sheet metal secured to each rib, the contiguous edges of said "petals" circumferentially overlapping when the basket is in normal position so as to enable the "petals" to move circumferentially with respect to each other and enable the basket to be collapsed about said tubing, the upper extremities of said ribs being curved inwardly and then upwardly to slidably engage the exterior of said tubing. 5 10 15
